CLAIM

The ornamental design for a hexagonal bulb seal, as shown and described.

DESCRIPTION

FIG. 1 is a perspective view of a hexagonal bulb seal, in accordance with the present invention;
FIG. 2 is a front elevation view of the hexagonal bulb seal, in accordance with the present invention;
FIG. 3 is a rear elevation view of the hexagonal bulb seal, in accordance with the present invention;
FIG. 4 is a right side elevation view of the view of the hexagonal bulb seal, in accordance with the present invention;

FIG. 5 is a left side elevation view of the hexagonal bulb seal, in accordance with the present invention;
FIG. 6 is a bottom plan view of the view of the hexagonal bulb seal, in accordance with the present invention; and,
FIG. 7 is a top plan view of the hexagonal bulb seal, in accordance with the present invention.

The dash-dash broken lines in FIGS. 1 to 7 illustrate environmental structure which forms no part of the claimed design.

The hexagonal bulb seal is shown broken along its length by dash-dot-dash broken lines depicting symbolic break lines to indicate that the hexagonal bulb seal may be any length, the dash-dot-dash broken line and space between forming no part of the claimed design.
